Patented July 16, 1918.

UNITED STATES PATENT OFFICE.

HANS ADELMANN, OF NEW YORK, N. Y., ASSIGNOR TO HAM BOILER CORPORATION, OF NEW YORK, N. Y., A CORPORATION OF NEW YORK.

HAM-BOILER.

1,272,883.

Specification of Letters Patent.

Patented July 16, 1918.

Application filed September 5, 1917. Serial No. 189,714.

To all whom it may concern:

Be it known that I, HANS ADELMANN, a subject of the Emperor of Germany, and resident of the city of New York, borough of 5 the Bronx, county of Bronx, and State of New York, have invented a new and Improved Ham-Boiler, of which the following is a full, clear, and exact description.

This invention relates to meat cooking appliances and has particular reference to ham boilers or the like of the general type covered by Letters Patent of the United States issued to the Ham Boiler Corporation on October 24, 1916, No. 1,202,637, November 15 21, 1916, Design No. 49,915, and November 28, 1916, No. 1,206,494.

Among the objects of this present improvement is to render a ham boiler more convenient with respect to the manipulation 20 of the meat and much more rapid with respect to the means for inserting and removing the meat.

Another object of the invention is to relieve the machine from certain awkward or 25 cumbersome extensions that obtain in the previous machines proposed for this purpose.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawing, which is a vertical central longitudinal section showing the complete apparatus in full lines with the cap located just within the main receptacle 35 and indicating in dot and dash lines the position of the cap and locking dogs when under maximum collapse or contraction.

Referring now more particularly to the drawing, the body 10 is of any suitable form 45 adapting it to receive a ham for molding and cooking the same and to impart to the cooked ham an appearance of having been wrapped with a cord while being cooked, as has been set forth in my previous patents. 50 The body 10 in this instance is formed with longitudinal ribs 11 along its closed bottom serving as means for supporting the same in erect position. At each end of the body is formed a rack 12 having transversely arranged teeth, the points of which project

outward and downward preferably in the same vertical plane. I prefer to form this portion of the device as a single casting of aluminum or other suitable metal including 60 the racks.

A cap portion 13 constituting a slidable closure for the body includes a substantially flat top portion 14 and a downwardly projecting skirt or flange 15. The side portions of the flange 15 are preferably fluted to correspond and coöperate with the ribs 16 projecting into or toward the center of the body. The inner surface of the top 14 is also preferably provided with a sufficient number of transverse ribs 17 to stiffen this 70 part of the device, said ribs also being made with sharp edges, serving to bite more or less into the ham or other piece of meat and hold the skin or wrapper that may be used thereon from slipping. The upper face of 75 the cover 13 is provided with a pair of upwardly projecting bosses 18 preferably formed integral with the cover and each provided with a central tapped hole 18' having 80 a vertical axis.

The third main portion of the machine consists of a bar 19 approximately straight along its lower face and more or less convexed longitudinally along its upper edge or face. This bar is formed at its ends with 85 a pair of knuckles 20 having transverse parallel holes 21, the knuckles extending somewhat below the plane of the main portion of the bottom of the bar. The crossbar in length is slightly greater than that of the 90 body 10, the vertical planes of the centers of the holes 21 being just beyond the planes of the points of the teeth in the racks 12. The bar is provided with a pair of downwardly projecting bosses 22 having smooth central 95 holes 22', the upper ends of which merge into enlarged openings 23 at the top of the bar. The end portions 24 of the bar between the openings 23 and the knuckles may be 100 more or less rounded to serve as handles in manipulating the device.

25 indicates a rigid dog having a hook or tooth 26 at its lower end adapted to engage beneath any one of the teeth of the rack 12. The upper end of the dog is hinged by means 105 of a pivot pin 27 to the knuckle 20, the pin passing through the transverse hole 21. This description of the dog at one end of the bar applies to that of the other end of the bar.

Each of the bosses 22 is arranged in ver- 110

tical alinement with but spaced from one of the bosses 18 and a strong spiral spring 28 is seated at one end around one boss and at the other end around the other boss. The 5 tendency of these springs is to force the cap or cover 13 downward and the bar upward with respect to each other. This tendency of the springs is resisted by a pair of screws 29 fitted loosely through the holes 22' of the 10 bosses 22 and fixed in the threaded holes 18' of the lower bosses, the heads 30 of the screws lying normally against the bottoms of the openings 23 within the bar. These 15 springs and pins are so designed as to limit the expansive action of the springs while the springs are under some suitable degree of compression, such compression being regulatable by screwing the screws more or less deeply into the holes 18'.

20 The operation of this device may be briefly summarized as follows in view of the foregoing specific description: After the ham is made, as the process is called in practice, by boning and trimming and arranging the 25 skin or wrapper thereon, it is plunged into the interior of the body 10 and the cap is then forced down upon the same with a moderate degree of force applied to the handles 24. This action puts the springs 28 30 under a moderate degree of compression which is maintained by the locking of the dogs with the racks. At this time the heads 30 of the screws may extend somewhat from the bottoms of the openings 23. During the 35 cooking of the ham there is some expansion thereof which is provided for by the springs 28, but limited by the opposing bosses 18 and 22 while the screws are adapted to slip up through the bar. The manipulation of this 40 device, therefore, is exceedingly rapid inasmuch as the operator, by bearing down upon the bar, is able to apply sufficient compression upon the raw ham when preparing the device for the cooker. At the same time the 45 natural expansion of the ham, during the cooking action, is amply provided for by the compressibility of the springs. The operator having his hands at the handles 24 may easily manipulate the dogs to either swing

them in or out as may be necessary by the 50 use of his fingers, but since the vertical planes of the pivots 27 are outward of or beyond the vertical planes of the teeth it will be noted that when the bar is depressed the dogs 25 normally swing by gravity away 55 from the teeth, thus facilitating the removal of the cover.

I claim:

1. In a ham boiler, the combination of a body receptacle having formed as an integral part of each end a vertical series of rack teeth which project outward and downward, a cover for the receptacle telescoping therewith, a bar having ends projecting over and beyond the vertical planes of the racks 65 aforesaid, members pivoted to the ends of the bar and having hooked coöperation with the rack teeth to hold the bar in fixed adjusted position with respect to the body, and resilient means interposed between the 70 cover and the bar.

2. In a ham boiler, the combination with a receptacle and a cover telescopically connected therewith, of a bar extending above the cover and longitudinally of the same and the receptacle, members pivoted to the ends of the bar and coöperating with the ends of the receptacle to hold the bar from upward movement, a pair of bolts connected to the cover and slidable through the bar and serving to limit the extent of relative separation of the bar and cover, and a pair of 80 springs acting between the cover and the bar tending to prevent relative movement of the cover and bar toward each other. 85

3. In a ham boiler, the combination with a receptacle and cover telescopically connected therewith, of a bar extending above and longitudinally of the cover, a pair of bolts extending between the bar and the 90 cover and fixed to one of them and slidable through the other, a pair of springs between the bar and the cover tending to keep the cover and the bar separated as far as will be permitted by the bolts, and means to lock the 95 cover and bar to the receptacle.

HANS ADELMANN.
